UNITED STATES PATENT OFFICE.

HARRY M. LIPPER, OF PHILADELPHIA, PENNSYLVANIA, ASSIGNOR TO LIPPER MANUFACTURING CO. INC., OF PHILADELPHIA, PENNSYLVANIA, A CORPORATION OF PENNSYLVANIA.

TEXTILE FABRIC AND METHOD OF MAKING THE SAME.

Application filed January 4, 1927. Serial No. 158,851.

My invention relates to a new and useful textile fabric and method of making the same, and it relates more particularly to a relatively narrow knitted textile band, 5 ribbon or braid, known in the trade as "hat braiding", formed of suitable threads to imitate straw or the like, and adapted to be assembled or sewed together in successive rows, to form a hat shape. 10 The particular material of which the hat braid of my invention is formed is an artificial cellulose thread or more particularly a viscose thread, known in the trade as "artificial straw" and comprising viscose threads, 15 of a consistency, thickness and texture resembling straw, particularly when made up into a fabric, tape or braid.

"Artificial straw" or viscose hat braiding made heretofore, possessed an inherent 20 defect, by virtue of the method and material employed in making the same. Thus, the hat braiding of this type was knitted upon a flat upright knitting machine, by forming separate or non-interlacing longitudinal rows of chain stitches, and passing transverse weft threads through the braid, 25 back and forth across the width thereof, to connect the separate parallel rows of chain stitches together, to form a unitary fabric structure. Due to the relatively 30 smooth character of the transverse cellulose or viscose threads, and the absence of any positive interengagement between the transverse connecting weft threads and the successive transverse rows of loops, of the longitudinal rows of chain stitches, said separate 35 rows of knitted chain stitches would have a tendency to slip or slide upon the transverse connecting weft threads, so as to separate from each other at points, and 40 to crowd or gather at other points, thereby producing a non-uniform texture in the completed braiding and hat product.

In order to overcome this defect of hat 45 braiding of this character, and in order to produce hat braiding which will be of uniform texture, and not liable to any irregular spacing of the parallel rows of knitted chain stitches thereof, I produce a braiding, according 50 to my invention, by forming a number of separate, parallel longitudinal rows of knitted chain stitches, upon an upright flat knitting machine, sufficient to cover the desired width of the tape braiding or fab-

ric, and of any suitable single or multiple 55 thread strands, and interlacing with said separate parallel rows of knitted chain stitches, transverse connecting or weft threads of a crinkled character, simultaneously with the formation of the successive 60 stitches or loops, thereby to connect said separate rows of knitted chain stitches into a unitary fabric structure, in which the successive longitudinal rows of chain stitches 65 are maintained fixedly upon the transverse connecting threads.

Due to the crinkled character of the transverse connecting threads, the separate longitudinal rows of chain stitches are maintained in substantially fixed and spaced relation to each other and not subject to slippage or sliding even though said transverse 70 crinkled connecting threads are merely passed through the loops and do not interlock with the same, but merely grip the latter by virtue of the irregular or crinkled character thereof.

The irregular or crinkled character of the transverse connecting threads may be caused by a number of different means, as 80 for instance by twirling or twisting a relatively flat or ribbon like thread of cellulose or more particularly viscose, of sufficient rigidity.

For the purpose of illustrating my invention, I have shown in the accompanying drawings, a form thereof which is at present preferred by me since it will give in practice satisfactory and reliable results, although it is to be understood that the various instrumentalities of which my invention consists can be variously arranged and organized and that my invention is not limited to the precise arrangement and organization of these instrumentalities as herein shown and 90 described.

Referring to the drawings,

Figure 1 represents a diagrammatic view of an upright flat knitting machine illustrating the general method of forming my 100 novel hat braiding or fabric.

Figure 2 represents a diagrammatic side elevation of the same.

Figure 3 represents a plan view on a greatly enlarged scale of a portion of the broiding, or fabric of my invention.

Figure 4 represents a plan view of a group of three threads which are employed in the

particular embodiment of my invention, illustrated in Figure 3, to form the transverse connecting weft strand.

Figure 5 represents a section on line 5-5 of Figure 4.

In carrying out my invention, I employ any standard or conventional upright, flat, latch needle knitting machine, illustrated diagrammatically in Figures 1 and 2. A series of separate longitudinal rows of chain stitches 1, 2, 3 and 4, are knitted simultaneously and in spaced relations to each other, by means of a corresponding series of latch needles 5, 6, 7 and 8. In the particular illustration in Figures 1 and 2, the separate and parallel longitudinal rows of chain stitches 1, 2, 3 and 4, are shown as being formed of double threads or "ends" 9 and 10, supplied from suitable spools 11 and 12. The threads 9 and 10 which go to make up the rows of chain stitches 1, 2, 3 and 4, are of a suitable cellulose composition or more particularly viscose, and are of a relatively smooth texture resembling straw.

The transverse connecting weft strand designated generally by the numeral 13, may also be composed of a single crinkled thread or a number of threads, as the threads 14, 15 and 16 illustrated in the drawing. Thus, in the particular illustration shown in the drawing, the transverse connecting weft strand 13 is composed of two crinkled viscose threads 14 and 15, having irregular surfaces and comprising preferably a twirled or twisted flat, ribbon-like band of viscose, and a smooth thread 16 which may be added to the weft strand 13, in order to impart thereto the desired tensile strength.

The weft strand 13 thus composed of one or more crinkled threads 14 and 15, and also including, if desired, a smooth thread 16, to impart tensile strength thereto, may be supplied from a single spool 17.

The weft or connecting strand 13 is then passed through a tubular weft carrier 18, forming part of the knitting machine, and adapted to be moved back and forth across the width of the tape, in timed relation to the operation of the needles 5, 6, 7 and 8 of the knitting machine. Thus, prior to each downward stroke of the needles 5, 6, 7 and 8, the weft carrier 18 is moved across the width of the braid or fabric, from one side to the opposed side thereof, thereby delivering and disposing the weft strand 13 across the series of warp strands 19, just prior to the completion of the stitch, thereby to enclose the transverse weft 13 in the transverse row of knitted loops thus formed.

By so positioning one or more crinkled transverse connecting or weft threads in the successive transverse rows of knitted chain stitches, the several separate longitudinal rows of knitted chain stitches are not only connected to each other, to form a unitary

fabric structure, but are also spaced from each other in a relatively fixed and permanent manner, so as to prevent any slippage or relative displacement of one with respect to the others.

It will now be apparent that I have devised a new and useful fabric and method of making the same, which embodies the features of advantage enumerated in the statement of the invention and the above description, and while I have, in the present instance shown and described a form thereof which is at present preferred by me since it will give in practice, satisfactory and reliable results, it is to be understood that such preferred form is susceptible of modification in various particulars, without departing from the spirit or scope of my invention or sacrificing any of its advantages.

Having thus described my invention, what I claim as new and desire to secure by Letters Patent is:—

1. A textile fabric comprising a series of non-interlacing longitudinal rows of knitted stitches of suitable thread and transversely extending crinkled threads interlaced with the successive stitches of the parallel rows and connecting the same to form a unitary fabric layer with the rows of knitted stitches maintained in fixed spaced relation to each other by said transversely interlaced crinkled threads.

2. A textile fabric comprising separate, parallel rows of knitted stitches of suitable thread and transversely extending crinkled cellulose threads interlaced with the successive stitches of the parallel rows and connecting the same to form a unitary fabric layer with the rows of knitted stitches maintained in fixed spaced relation to each other by said transversely interlaced crinkled cellulose threads.

3. A textile fabric comprising separate parallel rows of knitted chain stitches and transversely extending crinkled threads interlaced with the stitches of each of said rows to connect the same in substantially fixed spaced relation to each other to form a unitary fabric.

4. A textile fabric comprising separate, parallel rows of knitted chain stitches and transversely extending crinkled cellulose threads interlaced with the stitches of each of said rows to connect the same in substantially fixed spaced relation to each other to form a unitary fabric.

5. A textile braid of the character stated, comprising longitudinal rows of knitted stitches formed of relatively smooth cellulose threads and transversely extending crinkled cellulose threads interlaced with the rows of said knitted stitches to retain the same in substantially fixed spaced relation to each other.

6. A textile braid of the character stated,

comprising non-interlacing longitudinal rows of knitted chain stitches formed of relatively smooth cellulose threads and transversely extending crinkled cellulose threads interlaced with the rows of knitted chain stitches to connect the same into a unitary fabric, and to retain said rows of knitted chain stitches in substantially fixed spaced relation to each other.

10 7. The method of making textile fabrics which consists in knitting a series of separate, parallel, longitudinal rows of stitches of suitable threads in predetermined spaced relation to each other and interlacing crinkled threads with each of said rows of knitted stitches at suitable intervals simultaneously with the knitting of the stitches of said longitudinal rows, thereby to connect the latter in substantially fixed spaced relation to each other to form a unitary fabric.

15 8. The method of making textile fabric which consists in knitting separate, parallel, longitudinal rows of chain stitches of relatively smooth threads, and in predetermined spaced relation to each other and interlacing

a transverse crinkled thread with the parallel longitudinal rows of chain stitches, simultaneously with the formation of each successive stitch of the several rows, thereby 30 to connect the latter in substantially fixed spaced relation to each other to form a unitary fabric.

9. The method of making textile fabric which consists in knitting separate, parallel, 35 longitudinal rows of chain stitches of relatively smooth cellulose threads, and in predetermined spaced relation to each other and interlacing a transverse crinkled cellulose thread with the parallel, longitudinal 40 rows of chain stitches, simultaneously with the formation of each successive stitch of the several rows, thereby to connect the latter in substantially fixed spaced relation to each other to form a unitary fabric. 45

10. A textile fabric comprising parallel rows of knitted stitches and transversely extending crinkled threads interlaced with the stitches of each of said rows, so constructed as to maintain the same in substantially fixed spaced relation to each other. 50

HARRY M. LIPPER.
